UNITED STATES PATENT OFFICE.

JAMES A. MORRELL, OF POLAND, NEW YORK, ASSIGNOR OF TWO-THIRDS TO WALLACE E. BUTLER AND EUGENE J. KIRBY, OF CHICAGO, ILLINOIS.

COMBINED GRINDING AND DRYING APPARATUS.

SPECIFICATION forming part of Letters Patent No. 781,445, dated January 31, 1905.

Application filed March 31, 1904. Serial No. 200,940.

To all whom it may concern:

Be it known that I, JAMES A. MORRELL, a citizen of the United States of America, and a resident of Poland, in the county of Herkimer and State of New York, have invented certain new and useful Improvements in a Combined Grinding and Drying Apparatus, of which the following is a specification.

My invention relates particularly to apparatus for drying and grinding peat and similar pulpy substances.

The main objects of my invention are to provide a device adapted to dry and grind a moist material such as peat by a single continuous operation, to provide improved means for heating air and forcing same through the mass of a quantity of material during the process of grinding same, and to provide a suitable construction and arrangement of parts whereby the material which is being ground is agitated in suitable manner to permit a current of heated air to be passed through the mass of the same and whereby the material is caused to flow continuously through the grinding apparatus and in a direction opposite to the flow of air. I accomplish these objects by the device shown in the accompanying drawings, in which—

Figure 1 is a vertical section of a device constructed according to my invention and adapted for simultaneously grinding and drying peat. Fig. 2 is an elevation of one of the sets of grinding-teeth on the outer grinding member. Fig. 3 is an elevation of one of the sets of teeth on the inner grinding member. Fig. 4 is a top plan of the device shown in Fig. 1. Fig. 5 is a side elevation of the same.

In the construction shown an inner hollow conical grinding member 2 is rigidly secured to the supporting-platform 3 and is provided on its outer surface with a plurality of rows of grinding-teeth 4. The conical member 2 is disposed in an upright position and is surrounded by a hollow cylindrical grinding member 5, which is journaled on a vertical axis concentrically of the conical member 2. The cylindrical member 5 is provided on its inner surface with a plurality of sets of grind-

ing-teeth 6. The teeth 6 are set at an angle with the axis of the cylinder and are adapted to coact with the teeth 4 in suitable manner to shear the material between the grinding members and at the same time urge such material in a downward direction. The weight of the outer member 5 is carried by roller-bearings 7. The outer member 5 is rotated by means of a pinion 8, which meshes with an annular gear 9, which is rigid on the member 5. A plurality of rollers bearing on the sides of the member 5 resist the lateral thrust of the driving-gears. The bearings for the gear 8 and for the rollers 10 are omitted from the drawings for the sake of simplicity.

The walls of the conical member 2 are provided with perforations 11, which are preferably located immediately behind the teeth 4, so as to prevent their becoming clogged with material during the process of grinding. Air is forced into the lower end of the member 2 by means of a blower which is connected with the pipe 12, but is not shown in the drawings. The upper end of the member 2 is closed by a conical cap 13, so that the air can only escape from the interior of the member 2 through the perforations 11. The interior of the member 2 is of considerably greater capacity than the combined areas of the perforations 11 in order to delay the air to some extent in its passage through said member. The air within the member 2 is heated to a high degree by means of the steam-coils 14, which connect with a boiler. (Not shown in the drawings.)

The member 5 is open at both ends and is preferably constructed with double side walls separated by a lining 15 of asbestos or other non-conducting material. Suitable arms 16 connect the upper end of the member 5 with a pivot 17, journaled in the upper end of the member 2. Material is supplied at the upper end of the member 5 and is discharged through suitable apertures 18 in the platform 3 at the lower end of the member 5. An annular wall 19 directs the material discharged from the lower end of the member 5 toward the apertures 18 and prevents such material from spreading out upon the platform 3.

The operation of the device shown is as follows: Assume that the outer member 5 is continuously rotating in the direction of the arrow 20 in Fig. 4 and that pulpy material, such as moist peat, is being fed continuously into the upper open end of the member 5. The large lumps are broken into smaller fragments by means of the large teeth 6 and 4 at the upper parts of the grinding members. 10 These particles descend through the action of gravity, assisted by the downward pressure exerted by the inclined teeth 6 on the outer member 5, and are successively acted upon and broken up into smaller particles during their 15 descent toward the fine teeth at the lower ends of the grinding members. During this operation the heated air within the member 2 is forced outwardly through the perforations 11 by the pressure exerted by the blower, and 20 thus enters the mass of the material between the grinding members in the form of a large number of fine jets. This hot dry air passes upwardly through the mass of the material, absorbing the moisture from such material 25 and carrying it out at the top. It will be noticed that the opposed rows of teeth 4 and 6, separated by large spaces, will keep the material in a state of violent agitation during the process of grinding same, and thus permit of 30 the ready flow of the dry heated air through the mass of such material. The peat is finally delivered into suitable receptacles below the apertures 18 in a dry and finely-divided state, ready to be conveyed directly to the compressing 35 machinery. The effect of the inclined teeth 6 is to force the material both downwardly and inwardly toward the heated surface of the member 2.

The efficiency of the drying device depends 40 upon the temperature of the drying-air, and for this reason it is preferred to superheat the steam before its admission to the heating-coils. With superheated steam a high temperature in the coils may be had with moderate steam-pressure. The superheating device is omitted from the drawings.

The brushes or scrapers 21, secured to the lower edge of the rotating cylindrical member 5, prevent the accumulation of material on 50 the platform 3 between the apertures 18.

It will be seen that numerous details of the construction shown may be altered without departing from the spirit of my invention.

What I claim as my invention, and desire to 55 secure by Letters Patent, is—

1. A combined grinding and drying apparatus, comprising a grinding member having perforated walls; a second grinding member coacting with the first member; an air-heater; 60 and means for forcing air from said heater through the perforations in said first member into the space between the members, substantially as described.

2. A combined grinding and drying apparatus, comprising a hollow grinding member 65

having perforated walls; a second grinding member coacting with the hollow member; an air-heater; and means for forcing air from said heater through the perforations in said hollow member and into the space between 70 said members, substantially as described.

3. A combined grinding and drying apparatus, comprising an inner hollow grinding member having perforated walls; an outer grinding member surrounding said inner member and adapted to coact with the same for grinding material placed between the walls of 75 said members; an air-heater; and means for causing air from said heater to flow outwardly through the perforations of the walls of said inner member and into the mass of the material between said members, substantially as described.

4. A combined grinding and drying apparatus, comprising an inner hollow grinding member 85 having perforated walls; an outer grinding member surrounding said inner member and adapted to coact with the same for grinding material placed between the walls of said members; an air-heater; and means for 90 causing air from said heater to flow outwardly through the perforations of the walls of said inner member and into the mass of the material between said members; and an outer non-conducting covering adapted to prevent 95 the loss of heat from said outer member, substantially as described.

5. A device of the class described, comprising an inner conical grinding member; an outer member surrounding said conical member and adapted to coact therewith for grinding material placed between said members; an air-heater; and means for causing air from 100 said heater to flow through the mass of the material between said members, substantially 105 as described.

6. A device of the class described, comprising an inner conical grinding member; a cylindrical outer member surrounding said conical member and adapted to coact therewith 110 for grinding material placed between said members; an air-heater; and means for causing air from said heater to flow through the mass of the material between said members, substantially 115 as described.

7. A device of the class described, comprising an inner conical grinding member; a cylindrical outer member surrounding said conical member and adapted to coact therewith for grinding material placed between said members; an air-heater; and means for causing air from 120 said heater to flow through the mass of the material between said members, one of said members having thereon a plurality of inclined shoulders adapted to normally urge the material between said members in a longitudinal direction, substantially as 125 described.

8. A device of the class described, comprising an inner conical grinding member; a cy- 130

lindrical outer member surrounding said conical member and adapted to coact therewith for grinding material placed between said members; an air-heater; and means for causing air from said heater to flow through the mass of the material between said members, said outer cylinder having thereon a plurality of inclined shoulders adapted to normally urge the material to flow in a longitudinal direction between said members, substantially as described.

9. In a device of the class described, the combination of a vertically-disposed hollow conical grinding member having perforated walls; a heating-coil secured within said member; an outer cylindrical member surrounding said conical member and open at the top and bottom; a plurality of grinding-teeth on said cylindrical member adapted to coact with said conical member for grinding material between said members and normally urging such material in a downward direction; and

means for causing a flow of air from the interior of said conical member outwardly through its perforated walls and through the mass of the material between said members, substantially as described.

10. In a device of the class described, the combination of an inner fixed conical grinding member; an outer cylindrical grinding member rotatable around said conical member and adapted to coact with said conical member for grinding material between said members; an air-heater; and means for causing air from said heater to flow through the mass of the material between said members, substantially as described.

Signed at Poland this 25th day of March, 1904.

JAMES A. MORRELL.
